UNITED STATES PATENT OFFICE.

ARTHUR C. MILLER, OF CLEVELAND, OHIO, ASSIGNOR TO THE THEODOR KUNDTZ COMPANY, OF CLEVELAND, OHIO, A CORPORATION OF OHIO.

DESIGN FOR A COMBINED SCHOOL DESK AND CHAIR.

49,036.

Specification for Design.

Patented May 9, 1916.

Application filed March 10, 1916. Serial No. 83,441. Term of patent 14 years.

To all whom it may concern:

Be it known that I, ARTHUR C. MILLER, a citizen of the United States of America, residing at Cleveland, in the county of Cuyahoga and State of Ohio, have invented and produced a new, original, and ornamental Design for a Combined School Desk and Chair, of which the following is a specification, reference being had to the accompanying drawing, forming part thereof.

The figure is a perspective view of a combined school desk and chair showing my new design.

I claim:

The ornamental design for a combined school desk and chair, as shown.

ARTHUR C. MILLER.
